GARMENT

Samuel J. Dichter, Chicago, Ill., assignor to Martha Maid Manufacturing Co., Chicago, Ill., a corporation of Illinois.

Application July 30, 1934, Serial No. 737,618

2 Claims. (Cl. 2—73)

This invention relates to a garment.

It is an object of this invention to provide an improved garment which is relatively simple and inexpensive in construction and efficient in use.

5 The garment forming the subject matter of
the present invention while being applicable to
garments, in general, especially relates to the
class of women's undergarments known as
"slips". Heretofore as these garments have been
10 constructed or made they have had a number
of objectionable features, among which have
been: the slips heretofore made, when in use,
have had a decided tendency to hang loosely and
bulge outwardly below the armpits of the wearer,
15 thereby presenting an unattractive, unsightly
appearance, particularly when worn with sleeve-
less dresses. Likewise, the slips heretofore made,
when in use, have had a tendency to chafe the
body of the wearer due to the side seams with
20 which they have been provided and which have
customarily extended vertically down the sides
of the slip from a point below the armpits; while
another objection to which such slips heretofore
made have been subject is that they have been
25 devoid of any elasticity or yieldability and hence
have been unable to shape and conform them-
selves neatly to the body of the wearer if slightly
oversize or undersize for the wearer, thereby mak-
ing it necessary that the purchaser, at the time
30 of purchase, buy the exact size of garment
required.

It is, therefore, an object of this invention to provide an improved woman's undergarment or slip which in use overcomes the aforementioned and other objectionable features of the prior art garments or slips and the difficulties experienced in the use of the same.

Another object of the invention is to provide a woman's undergarment or slip which is so made that when worn, it fits neatly and closely upon the body of the wearer, does not bulge or hang loosely under the armpits, nor chafe or irritate the body of the wearer under the armpits, and which is possessed of a considerable amount of elasticity or yieldability so that it will fit neatly and comfortably upon the wearer and present a neat, attractive appearance when in use even though the slip may be considerably oversize or undersize for the particular wearer.

Other objects will appear hereinafter.

The invention consists in the novel combination and arrangement of parts to be hereinafter described and claimed.

55 The invention will be best understood by refer-

ence to the accompanying drawing, showing the preferred form of construction and in which:

Fig. 1 is a perspective front view of a woman's undergarment or slip embodying the invention:

Fig. 2 is a rear perspective view of the garment shown in Fig. 1; 5

Fig. 3 is a perspective view illustrating the garment shown in Figs. 1 and 2 in use; and

Fig. 4 is a plan view of a section of material embodied in the new garment. 10

A woman's undergarment or slip embodying the invention is generally indicated at 10 in the drawing and comprises a body portion or bodice 11 and a skirt portion 12, the skirt portion 12 including front and rear sections 13 and 14, respectively. 15

It has been customary heretofore in the art of making garments of this nature, that is, slips, to form the bodice 11, in general, of two similarly shaped equal sections and to join both the front and rear sections of the bodice 11 by means of seams extended vertically downwardly from the lowest points of the edges 15 which define the armpit openings or arm holes. A number of objectionable features have always been present in the slips heretofore made, in general, in the manner stated, and among these objectionable features were that when in use those portions of the slip which define the marginal edges 15 of the armpit openings or holes have had a decided tendency to hang loosely and bulge out through the armpit openings or holes of the outer and overlying garment or dress of the wearer; while at the same time the vertical side seams would chafe and irritate the body of the wearer below the armpits. Moreover, such slips, even if only slightly undersize for the wearer would not yield or stretch to conform to the body and size of the wearer but would bind and fit uncomfortably, while if they were even slightly oversize they would hang loosely about the body or bust of the wearer and wrinkle and hang loosely under the armpits and out through the armholes or openings.

To overcome the foregoing and other objectionable features of the slips heretofore made and used, I embody in the bodice 11 of the new slip two irregularly shaped fabric sections or panels 18 (Fig. 4) which are, preferably, cut on the bias from the material or stock from which they are made; each of these sections being defined by the marginal edges 15-17-16-21-20-22. 45 50

The side seams of the bodice 11 are defined by the edges 16 of the panels or inserts 18, and extend forwardly, as shown in Figs. 1 and 3. The 55

side seams 16 merge by short end portions 17 into the marginal edges 15 of the armholes, and extend forwardly of the armpits over the bust of the bodice above the lowest point of the armhole openings; while the marginal back seams or edges 21 of these inserts of panels 18 meet at the back of the slip along the center seam 20 (Fig. 2).

Each of the sections 18 includes a portion 19 and these portions 19 extend forwardly over the bust of the bodice and are coincidental along their upper edges with the marginal edges 15 of the armpit openings.

The irregularly shaped or patterned inserts or panels 18 are preferably, but not necessarily, cut on the bias from the stock of material from which they are taken, but, in either event, when the new slip is in use stretching and other strains exerted upon the irregularly shaped sections 18 are exerted thereon at an angle relative to the long axes of the threads or fabric of which such sections are composed; these strains being exerted on the inserts or sections 18 in such a manner that the latter are bound close to the body of the wearer and particularly over the bust and back and under the armpits of the wearer. Moreover, this construction imparts considerable elasticity to the bodice of the slip, into which they are incorporated; and, by reason of this fact, and the additional fact that these sections 18 extend forwardly over the bust of the bodice of the slip, and around the sides of the bodice and rearwardly over the back thereof, the new slip fits tightly and closely to the body of the wearer all over the bodice and bust portions thereof, as well as under the armpit openings or holes, and therefore presents a neat, attractive appearance when in use. Furthermore, the side seams 16 of the bodice, being continuous with the side seams 23 of the skirt, do not bind or chafe the body of the wearer under the armpits, as in the slips heretofore made.

Moreover, when the panels or inserts 18 are cut on the bias, as in the preferred form of construction, they impart still more elasticity or yieldability to the bodice of the slip which enables it to stretch and conform to the size of the wearer so that the garment may readily be slipped on by the wearer and comfortably worn even though it may be considerably oversize or undersize for the wearer, which was not possible in slips heretofore made and used and constructed in the manner hereinbefore set forth.

The new garment 10 thus overcomes the aforementioned and other objectionable features of the slips heretofore made and used and accomplishes its intended objects, and has the advantages, hereinbefore set forth.

It is to be noted that when the present garment is in use the curved front edges 16 of the rear panels 18 tend to straighten out into substantially straight side seams which have their maximum

curvature approximately midway between the waistline and the armpit openings of the garment, as may be seen by a comparison of the curvature of the front edge 16 in the rear panel 18, which is shown in plan in Fig. 4, with the curvature of the front edge 16 of the rear panel 18 as shown in Fig. 1. This places the rear panels 18 under stress when the garment is in use and thereby causes the same to fit tightly to the body of the wearer throughout those areas of the garment through which the curved front edges 16 of the rear panels 18 extend.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims. Thus, while I have specifically described the invention as applicable to a "slip" the same is not limited to this particular type of garment but may likewise be applied to other garments including dresses and the like.

Having thus described my invention, what I claim as new and desire to protect by Letters Patent is:

1. In a slip, a skirt, and a bodice portion; said bodice portion including a front panel and a rear panel having a curved front edge extending upwardly and forwardly from the waist line of the garment over the bust of the same; said edge being sewed to the said front panel and having its maximum curvature approximately midway between the waistline and the armpit opening of the garment; the said curved edge tending to straighten out, when the garment is in use, into a substantially vertical or straight side seam so as to place the said panel under stress and thereby cause the same to fit tightly to the body of the wearer throughout that area of the garment through which said curved front edge extends.

2. In a slip, a skirt, and a bodice portion; said bodice portion including a front panel and rear panel having a concavely curved front edge extending upwardly and forwardly from the waist line of the garment over the bust of the same; said edge being sewed to the said front panel and having its maximum curvature approximately midway between the waistline and the armpit opening of the garment; the said curved edge tending to straighten out, when the garment is in use, into a substantially vertical or straight side seam so as to place the said panel under stress and thereby cause the same to fit tightly to the body of the wearer throughout that area of the garment through which said curved front edge extends.

SAMUEL J. DICHTER.
